UNITED STATES PATENT OFFICE

136,251

DESIGN FOR AN EGG SEPARATOR

Joanne Clark, Los Angeles, Calif.

Application May 29, 1943, Serial No. 110,322

Term of patent 7 years

To all whom it may concern:

Be it known that I, Joanne Clark, a citizen of the United States, residing at Los Angeles, in the county of Los Angeles, State of California, have invented a new, original, and ornamental Design for an Egg Separator, of which the following is a specification, reference being had to the accompanying drawing, forming a part thereof, in which:

Fig. 1 is a top plan view of an egg separator, showing my design;

Fig. 2 is a sectional elevation thereof taken through 2—2 of Fig. 1; and,

Fig. 3 is an exploded view of the two members of my egg separator and shown in section as in Fig. 2.

I claim:

The ornamental design for an egg separator, substantially as shown.

JOANNE CLARK.
